READING STAND

Filed April 12, 1928

UNITED STATES PATENT OFFICE

HAZEL ERNEST WEST, OF WASHINGTON, DISTRICT OF COLUMBIA

READING STAND

Application filed April 12, 1928. Serial No. 269,530.

The present invention relates to improvements in reading stands, and has for an object to provide a stand adapted for use by anyone lying down, and especially in connection with beds whereby patients and convalescents may, while in a reclining or fully supine position, be enabled to occupy themselves with reading, without expending energy in the holding of the book.

10 It is another, and very particular object of the invention to provide a transparent book holder, which may assume a substantially horizontal position directly over the bed and head of a reader, with the book in open position and supported face downward on the holder whereby the text may be read through such transparent holder.

15 The invention may also be used as a table for writing or typewriting purposes, or other uses as a table.

20 Further objects of the invention are to simplify, and reduce the expense of manufacture of present forms of book stands; to provide a wide range of adjustability in the book holder; and to provide a light, portable and easily adjusted construction.

25 With the foregoing and other objects in view, the invention will be more fully described hereinafter; and will be more particularly pointed out in the claim appended hereto.

30 In the drawings, wherein like symbols refer to like or corresponding parts throughout the several views,

35 Figure 1 is a perspective view of the improved reading stand shown as applied to the bed indicated in dotted lines.

40 Figure 2 is a side elevation of the improved reading stand taken on an enlarged scale, and with parts broken away and parts shown in section.

45 Figure 3 is a front elevation with the book holder shown in section.

Figure 4 is a vertical longitudinal section taken through the universal joint connection.

Figure 5 is a horizontal section taken on the line 5—5 in Figure 4.

50 Figure 6 is a vertical section taken on the line 6—6 in Figure 4.

Figure 7 is also a vertical section taken on the line 7—7 in Figure 4, and

Figure 8 is a perspective view of a portion of the frame for the transparent book holder.

Referring more particularly to the drawings 9 designates a table of glass, or other transparent material, which forms the book holder with the frame which receives and supports the glass sheet. This frame 10 may be of any appropriate form and preferably consists of the four channel strips for extending over the four edges of the rectangular glass sheet or table 9. In addition, the book holder may also be provided with the device shown in Figure 8 comprising the channel arms 11; cross connecting piece 12 and the book supporting ledge 13. The channel arms 11 may be reinforced by the longitudinal ribs 14. The arms 11 are received over the frame 10, as shown in Figures 1 and 3.

One member of the frame 10 is provided with the stem 15 carrying the universal ball 16 fitting adjustably within the partially spherical depressions 17 and 18 near the free ends of the two legs 19 and 20 of the metallic yoke piece, which comprises the legs just referred to and the connecting cross member 21. The yoke may be made of sheet metal or other appropriate, preferably resilient material. A block or partition wall 22 is inserted between the legs 19 and 20 about midway of the length thereof and outwardly beyond such wall are the screw bolts 23 or other adjusting means by which the free ends of the legs 19 and 20 may be drawn together with more or less pressure upon the universal ball 16.

The wall 22 and connecting piece 21 of the yoke member are both provided with straight-line openings, for instance, the rectangular openings shown in Figure 7 to receive the ends of the square or other straight-line tube 24. The universal ball 16 is provided with a socket 25 diametrically opposite the stem 15. Now this socket is adapted to be received on pin 26, preferably round in cross section to agree with the similar cross section of the socket 25. The pin 26 is carried on the end of a straight-line,

or square shank 27 which projects substantially horizontally from the post rod 28, and engages the ball 16, thus forming a rigid joint when an abnormally heavy weight rests 5 on the table 9. The supporting post comprises the rod 28, intermediate sleeve 29 and outer sleeve 30. A set screw 31 is carried by the intermediate sleeve for adjusting the rod 28 longitudinally therein. The intermediate 10 sleeve 29 may be held in its adjusted position in the outer tube 30 by frictional resistance, or clamped at the desired position by a set screw, not shown. The outer tube 30 is erected on a relatively short cross bar 15 32 having the spaced feet 33 and 34 to diametrically opposite sides of the post. The cross bar 32 is provided with the divergent hollow leg members 35 and 36 extending from opposite ends of the cross piece and receiving 20 the adjustable leg rods 37 and 38; these may have the down-turned ends 39 for engaging the floor to support the hollow leg members and rods 37 and 38 spaced above the floor. These downwardly projecting lugs 25 33, 34 and 39 may be omitted if desired.

The rods are provided with downwardly extending projections 40 to fit in longitudinal slots 41 in the lower portions of the hollow leg members to avoid the relative rotation 30 of these parts, which might otherwise result in the turning of the ends 39 out of contact with the floor.

In the use of the device, a book is represented at 42 in Figure 1, as being in the open 35 position and face downward upon the glass holder 9, while such holder assumes a horizontal position extending directly over the pillow on which it is assumed the patient reclines in fully supine position, looking up 40 through the glass 9 and reading the text of the book, which is presented to him through such transparent book holder.

The legs extend beneath the bed and give and yield widely spaced points of support; 45 while the post rises at the side of the bed and enables the book holder to be carried above the bed. The book holder may be turned on a horizontal axis coinciding with the axis of the stem 15 and pin 26, when the pin is 50 engaged in the socket 25. This plane of adjustment is indicated in Figure 3 and may be useful in supporting the book in a more or less vertical position with the book resting on the ledge 13, as for reading when propped 55 up in bed or in a substantially sitting posture. The resiliency and frictional binding of the yoke legs upon the universal ball will retain the book holder in the adjusted position. Now the shank 27 is square or of other 60 straight line configuration and it prevents the rotation thereabout of the yoke piece.

The shank 27 is adjustable longitudinally through the square tube 24 for the purpose of inserting and withdrawing the pin 26 from 65 the socket in the ball. When this pin is with-

drawn the shank 27 still supports the yoke and book holder, but it gives entire freedom of adjustment in universal directions, which were not permitted when the pin was engaged in the socket. 70

The device may be also useful as a table, but its greatest utility is in supporting the book, as shown in Figure 1, for a weak or inert recumbent person, to be enabled to read without in any way supporting the book or being obliged to assume a more erect posture. 75

While the various posts, cross bars, and other parts of the frame work are shown as round in cross section, obviously these may be made rectangular or of any desired angular cross section. 80

It is obvious that various changes and modifications may be made in the details of construction and design of the above specifically described embodiment of this invention without departing from the spirit thereof, such changes and modifications being restricted only by the scope of the following 90 claim.

What is claimed is:—

A reading stand, comprising a base portion adapted to rest on a support, a post rising from one end of the base portion and bent horizontally at its upper end to provide a fixed pin overhanging the base portion, a clamping member pivotally mounted on the pin and having socketed clamping jaws spaced from and extending outwardly of the pin, a ball disposed between the sockets of the clamping jaws and having an opening in one side to receive the pin and hold the ball from turning in the vertical plane of the pin, clamping means for binding the jaws against the ball to hold it when adjusted about the axis of said pin, a stem carried by the ball and extending outwardly therefrom on the axis of said pin, and a supporting frame mounted on the outer end of the stem adapted for adjustment with the ball and stem on the axis of said pin. 100
